(57) **CLAIM**

The ornamental design for a camera, as shown and described.

DESCRIPTION

FIG. 1 is a front, left, and top perspective view of a camera showing our new design;

FIG. 2 is a rear, right, and bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a right side elevational view thereof shown extended in a state of use;

FIG. 10 is a front, left and top perspective view thereof shown in a state of use with a phone in broken lines; and, FIG. 11 is a front, left, and top perspective view thereof in a second state of use with a tablet shown in broken lines.

The broken lines in the figures are shown for the purpose of illustrating portions of the camera, and/or environmental matter and form no part of the claimed design. Additionally, the dash-dot lines denote the boundary of the claim and form no part of the claimed design. The extendable portion is shown broken away in FIG. 9 to indicate that no particular length is claimed.
